Inventor,

Joseph B. Burfoot.

UNITED STATES PATENT OFFICE.

JOSEPH B. BURFOOT, OF MOBILE, ALABAMA.

MECHANICAL TOY.

SPECIFICATION forming part of Letters Patent No. 399,015, dated March 5, 1889.

Application filed November 15, 1888. Serial No. 290,838. (No model.)

To all whom it may concern:

Be it known that I, JOSEPH B. BURFOOT, a citizen of the United States, residing at Mobile, in the county of Mobile and State of Alabama, have invented new and useful Improvements in Mechanical Toys, of which the following is a specification.

My invention relates to improvements in mechanical toys; and it consists in certain novel features, hereinafter described and claimed.

In the accompanying drawings, Figure 1 is a side view of my improved toy. Fig. 2 is a view showing the frame and handle in vertical section and the rotating disks and rod in elevation. Fig. 3 is a detail view showing a modification of the upper end of the rotary rod, and Fig. 4 is a detail view showing the manner of securing the disks to the rod.

Referring to the drawings by letter, A designates the handle, which may be of any desired size and design, and has secured to its upper end a shelf or platform, B, and provided in its upper portion with an interior vertical socket, C, as shown. At the corners of the platform B, I erect the columns or supports D D, upon which I secure the roof or cover E, as shown.

F designates the central rotating rod, having its lower end journaled in the socket C, and provided with an annular groove, G, which is engaged by the inner end of a pin, H, inserted transversely through the handle, so that the said rotating rod will be prevented from slipping from the handle in the operation of the device. The upper end of the said rod extends through the bottom plate of the roof or cover E, and is turned to one side, forming a horizontal arm, I, to the end of which is secured a weighted ball, J, by any desired means. The vertical portion of the rotating rod is provided at proper points with the laterally-projecting tongues or offsets K, which are adapted to support the disks L, as shown.

If desired, these projecting tongues or offsets may be dispensed with and the disks fastened to vertical rods by being soldered or glued or forced into position by pressure.

Upon the said disks L, I secure suitable fig-

ures to represent soldiers, engines, ships, &c., as shown.

The construction of my device being thus made known, the manner of using the same will be readily understood. The toy is grasped by 55 the handle and tilted slightly to one side, thereby disturbing the equilibrium and causing the ball J to roll to the lowest point of the roof, thereby rotating the rod F and carrying the disk around with the said rod, so 60 that the figures on the said disks will appear to be moving of their own volition.

It will be observed that my toy is composed of very few parts and is extremely simple in its arrangement, so that it can be manufactured and sold at a small cost. The ball which rotates the central rod is hidden by the roof, so that the deceptive appearance of the figures in motion is complete. The device can be constructed of any suitable material, 70 such as sheet metal or pasteboard. I prefer to erect the columns or supports at each corner of the platform; but, if so desired, they may be erected only at the front corners of the platform, so as to represent the front of a 75 theatrical stage.

It may sometimes be preferred to construct the upper end of the rotating rod as shown in Fig. 4. In this form of my device the upper end of the said rod is extended upward 80 through the roof, and has a small flag secured to its extremity, as shown. A horizontal arm, I, may be formed integral with the rod, or else formed separately and secured thereto, as will be readily understood. It may also be preferred sometimes to dispense with the horizontal arm and secure the ball to the under side of the lower disk, so that it will rest on the platform, as shown in dotted lines in Fig. 1, the upper end of the rotating rod being extended through the roof and provided with a flag, as also indicated in dotted lines in said figure. These changes obviously involve no departure from my invention.

Having thus described my invention, what I 95 claim, and desire to secure by Letters Patent, is—

1. A toy comprising a handle, a rotatable rod swiveled in the handle, a series of disks secured to said rod and rotated thereby and 100

having images secured upon their upper sides, and a weight secured to the rod independently of the disks, whereby when the handle is tilted the weight will fall and the rod be 5 rotated, as set forth.

2. A toy comprising a handle, a rotatable rod swiveled in said handle, an arm extending laterally from the said rod, a weight secured to the end of said arm, and a series of 10 disks secured to and rotated by the rod and having images secured on their upper sides, as set forth.

3. A toy comprising a handle, a roof supported by the handle, a rod mounted in the 15 handle and having a ball connected to its upper end and adapted to move over the bottom plate of the roof, and the disks secured to the said rod and carrying figures, as set forth.

4. A toy comprising a handle, a rod mounted 20 in said handle and having laterally-projecting tongues or offsets; disks secured to the handle and carrying figures, and a ball connected to the said rod to rotate the same, as set forth.

5. The improved toy herein described and 25 shown, comprising the handle having a socket in its upper portion, the platform secured to the upper end of the handle, the columns erected on the platform, the roof supported by the columns, the rod having its lower end 30 journaled in the socket in the handle and provided with an annular groove, and having its upper end bent to one side, the pin inserted transversely through the handle and engaging the annular groove of the said rod, 35 the ball secured to the upper end of the said rod, and the disks secured to the said rod and carrying figures, as set forth.

In testimony that I claim the foregoing as my own I have hereto affixed my signature in 40 presence of two witnesses.

JOSEPH B. BURFOOT.
